UNITED STATES PATENT OFFICE

FREDERIC G. NICOLAUS, OF CLEVELAND, OHIO, ASSIGNOR TO AMERICAN STOVE COMPANY, OF ST. LOUIS, MISSOURI, A CORPORATION OF NEW JERSEY

DETACHABLE PLATE FOR CONCEALED MANIFOLDS OF GAS RANGES

Application filed April 22, 1929. Serial No. 357,106.

This invention relates to certain improvements in detachable plates for concealed manifolds of gas ranges as will be shown and described hereinafter.

5 The present improvement is on the detachable plate for concealed manifolds shown in patent to Joseph Roy No. 1,643,176 dated September 20, 1927 and on the plate shown in patent to F. G. Nicolaus No. 1,637,870

10 dated August the 2nd, 1927.

Each of the plates shown in these two patents is provided with vertical openings through which the handles for the valves located inside of the oven project. Stoves having plates provided with the vertical slots have been manufactured and sold with these vertical slots and it is the primary object of the present invention to make a plate for concealing the manifold valves and valve housings without these vertical slots. It has been

20 found difficult to provide a plate of the character herein described without these vertical slots and at the same time provide some means to connect the handles with the valves 25 located in the said range housing.

After considerable experimenting I have 30 finally been able to produce a plate for concealing the manifold without any vertical slots and to so construct the handle that it can be operated from outside of the range structure.

Such a structure broadly consists in so arranging the plate as to provide a horizontal opening at its lower edge and to so shape the 35 handle that it passes around the said plate and through the slot to the inner side of the housing and connecting its inner end with the valve located in the said housing, the operating portion of the handle located in substantially the same position as the handles in the aforesaid patents.

40 Specifically this arrangement provides a handle so constructed that it extends around the lower edge of the plate and through the slot and connected with the said valve, the handle thus being substantially U-shaped in end view whereby when the handle is up the valve is on and when the handle is in its downward position the valve is off, thus enabling the gas to be turned on and cut off as

may be desired. It must also be understood that these positions can be reversed, namely, that the valve be provided with its openings so located that when the handle is in its upward position it will be off and when in its downward position it will be on. However the position here indicated is the preferred position for turning the gas off and on.

55 Referring now to the drawings:

Figure 1 is a perspective view of the top burner portion of a range with my improvement applied thereto.

Figure 2 is a vertical sectional view taken through the plate showing the construction and locations of the said plate operating handle valve housing and manifold which are enclosed within the housing.

Figure 3 is a front view of a portion of Fig. 1 the said valve housing and manifold being shown in dotted lines.

Figure 4 is a detached horizontal cross sectional view taken through one of the valve housings and the operating lever connected with the valve.

Figure 5 is a detached perspective view of the operating handle.

Certain modifications can be made in the specific construction here shown without varying from the invention as defined in the accompanying claims. Referring now particularly to the exact construction here shown for putting into effect the present improvement, 1 indicates the housing of the top burner portion of a gas range and 2 shows only a part of the lower portion of the oven.

80 In the construction here shown the top burner portion 3 comprises so far as the present improvement is concerned a plate 4 which is angular in cross section, the front edge 5 of this plate extends downward. One or more brackets 6 are connected to the inner side of the downwardly extending leg or portion 5 by means of a suitable screw 7. This bracket has its lower edge 8 extending inward substantially as shown.

85 A substantially vertically arranged plate has its upper edge 9 extending outward and abutting against the under side of the arm 8 the plate being connected with the bracket by a suitable screw 10. This plate in the 90

95

100

95

special construction here shown has a downwardly extending portion 11 and from the lower edge of the portion 11 a plate then is curved inward as shown at 12, the lower edge 5 of the plate stopping slightly above a suitable removable tray 14 located under the top burner portion 3. It will be observed from the foregoing description that there is formed between the lower edge 13 and the top tray 10 14 a slot 15 for the reception of a lever that will now be described.

A lever constructed to operate the valve 16 has its lower end 17 attached to the outer end of the valve 16 by means of a suitable 15 screw 18. This lever has its attached end extending inward at right angles to the valve, is then bent outwardly as at 19 and then is curved around the lower edge 13 of the plate 11 to the outer side of the plate as 20 clearly shown in Figures 2 and 5 at 20. The outer extremity of this lever has attached to it a handle 21 by which the lever is moved up and down and consequently the valve is correspondingly moved for cutting off and 25 turning on the gas to a suitable nipple 22 that feeds the gas to a burner not shown. As here shown the laterally turned portion 19 of the lever is attached to the curved portion 20 by having the abutting portions spot 30 welded as shown at 23, which is found to be the preferable way. However it will be understood that the lever could be made so that the parts 17 and 19 would be integral with the part 20 without varying from the construction here described. The housing 24 for 35 the valve 16 has extending from its upper side a suitable nipple 25 that enters the manifold 26 extending inside of the housing of the top burner portion.

40 From the foregoing description the operation of this improvement will be understood it being only necessary to state that this improved construction provides a range with a top burner portion having the manifold 45 concealing plate 11 and a special construction of the handle to pass around the said plate and thus avoid the necessity of having vertical openings therein for the passage of the operating handle.

50 In the construction here shown it will also be understood that by removing the screws 10 that hold the plate to its bracket 6 enables the plate to be removed from the front side of the burner top 3 thus exposing the valve, 55 valve housing and other parts for repair or substitution or other purpose.

Having thus described my invention what I claim and desire to secure by Letters Patent is:

60 1. A burner top for gas ranges having a concealing manifold comprising a depending plate attached with the said top leaving a space at its lower edge, a valve located behind said plate and a lever having its inner 65 end curved around the said plate and passing

through the said space and attached to the end of the valve leaving an exposed outer portion, whereby it can be opened and closed.

2. A concealed manifold for top burner portions of gas ranges comprising a top portion, a plate connected with the top portion and extending downward to leave an opening at its lower portion, a valve housing and a valve located behind the said plate and a substantially U-shaped lever having its inner 70 end connected with the said valve and its outer end extending around the said plate and carrying the handle whereby the valve can be moved to open and shut positions by raising and lowering the said handle.

3. A concealed manifold for top burner portions of gas ranges, the top portion enclosing a manifold, a downwardly extending plate having its lower edge stopping to form a horizontal slot, a valve housing in 85 communication with the manifold having also a gas passageway for supplying a burner, of a lever substantially U-shaped and passing through the said slot around the said plate, the inner end of the lever extending laterally and connected with one end of the 90 valve, the outer end of the U-shaped lever carrying an outwardly projecting handle for operating the movable parts.

4. A concealed manifold structure for gas 95 ranges comprising a top burner portion having its top with a downwardly extending flange, a plate detachably connected with said flange and extending downward leaving a horizontal slot at its lower end, a manifold 100 valve housing and valve located beyond the said plate in the said top burner portion and an operating lever having its lower portion substantially U-shaped and connected at its inner end to said valve and its outer end carrying an outwardly projecting handle 105 whereby the said valve is operated by the up and down motion of the handle.

5. A concealed manifold for top burner portions of gas ranges in which the top burner portion has extending downwardly therefrom and detachably connected thereto 110 a plate having its lower portion extending inwardly and forming a slot at its lower end, a valve and valve housing within the top burner portion and a substantially U-shaped lever having its inner end connected with said valve and having an outwardly extending handle connected with its outer end whereby the said parts are concealed and 115 operated by the up and down movement of the said handle.

6. A concealed manifold for top burner portions of gas ranges comprising a plate having its upper end connected with the top 125 burner portion and extending downward to leave a slot in its lower end, a valve housing and a valve behind the said plate, of an operating member consisting of a lever substantially U-shaped with its inner end extending 130

laterally and then inwardly towards the center of the U-shaped portion the inwardly part connected with the said valve and operating handle extending outward from the outer end of the U-shaped portion, for the purpose specified.

5 7. A burner top for gas ranges having a concealing manifold comprising a horizontally elongated plate located below the said top and supported to leave a space at one edge thereof, a valve located behind said plate, and a lever extending from outside the plate having its inner end curved around the said plate and passing through the said 10 space and attached to the end of the valve, whereby the valve can be opened and closed by moving the outer end of said lever.

In testimony whereof I hereunto affix my signature.

20 FREDERIC G. NICOLAUS.
